UNITED STATES PATENT OFFICE.

THOMAS F. CROCKER, OF CHICAGO, ILLINOIS, ASSIGNOR TO RESERVE HOLDING COMPANY, OF KANSAS CITY, MISSOURI, A CORPORATION OF DELAWARE.

AUTOMATIC TELEPHONE SYSTEM.

Application filed June 24, 1927. Serial No. 201,143.

This invention pertains to automatic telephone systems in general, but is more particularly concerned with telephone systems in which calls extended to dead or unequipped selector levels or to unequipped connector bank contact sets are automatically trunked to an intercepting operator. The object of the invention is the provision of new and improved trunk circuits for the trunks extending to the intercepting operator's position, and the provision of a new and improved intercepting operator's cord circuit for answering intercepted calls.

In an automatic telephone system of this kind in which intercepting service is provided, if a calling subscriber or a toll operator in attempting to set up a connection to a called subscriber dials a wrong digit, and as a result causes the automatic switch operated thereby to operate to an unequipped level, or to an unequipped set of bank contacts, the call will be trunked to the intercepting operator. The intercepting operator will then answer the call and inform the calling subscriber or the toll operator of the mistake, and also give him such information as she may have concerning the wanted subscriber.

Most commonly, in automatic telephone practice the toll operator sets up toll connections by dialing the directory number of the called subscriber, causing one or more selectors, one of which is termed a toll transmission selector, and a connector to successively operate and extend the connection to the called line. If the called line is busy, the operator receives the busy tone, but if the called line is idle, a supervisory lamp at her position lights, to apprise her that the called line is idle. In telephone practice, it is highly desirable that the operations performed by the toll operator and the supervision given be uniform, regardless of whether she has obtained connection with the wanted subscriber or has dialed a wrong number and has obtained connection with the intercepting operator.

The particular feature of this invention is the introduction of intercepting trunk circuits for the trunks extending from the unequipped selector levels, from the vacant toll transmission selector levels, and from the unequipped bank contact sets of the connectors extending to the intercepting operator, the characteristic of each of these being

such that when a call is extended thereto, the toll operator receives the same signals as though she had completed the connection to the wanted subscriber.

Another important feature of this invention resides in the new intercepting operator's cord circuit. In this new cord circuit are contained means for tripping the ring which functions when the operator inserts the plug of the cord into the jack of a trunk from unequipped connector bank contact sets to answer a call extended thereover, and which will refunction if a second call is extended to this same trunk before the intercepting operator has removed the plug. The ring tripping arrangement used is a modification of the arrangement disclosed in the application of V. S. Tharp, Serial No. 136,925, filed September 22, 1926.

In the following specification these features and others not specifically mentioned, and the operation thereof will be described in detail with the aid of the accompanying drawings comprising Figs. 1 and 2. These drawings illustrate by means of the usual schematic circuit diagrams the new and improved trunk circuits and intercepting operator's cord circuit introduced by this invention and also show diagrammatically the main switches of an automatic telephone system, operated in the extension of a connection from a toll operator to a called subscriber, with which the trunk circuits are associated.

The drawings to be most easily understood should be placed with Fig. 2 to the right of Fig. 1, with the corresponding lines in alignment. In the upper half of Fig. 1, a toll operator's cord circuit O terminating in the plug P and a trunk accessible at jack J and terminating in the selector S is shown. As many of such cords and trunks are provided as are necessary to take care of the service. The operator's cord circuit O may be of any suitable type and is therefore not shown in full; only those elements which concern the operation of the invention are shown. The selector S may be of any suitable type, such as the well known vertical and rotary type, having horizontal rows or levels of bank contacts. In the banks of this and other selectors in multiple in as many levels as is required, trunk lines are accessible to a number of groups of toll transmission selectors. The bank contact sets of the unequipped

levels, however, are multiplied together and connected to one or more trunks extending to the intercepting operator's position, such as the trunk comprising conductors 36', 37' and 38', terminating in the jack J', and having the associated trunk circuit TC'.

The intercepting operator is equipped with one or more cords such as a cord circuit O', terminating in the plug P'. The trunk circuit TC' and the cord circuit O' form a particular part of this invention and will be described in detail subsequently.

The trunk line comprising conductors 36, 37 and 38, and accessible at the bank contacts 6, 7 and 8 of the selector S, terminates in the toll transmission selector EF. The toll transmission selector EF shown only in skeleton, may be of any suitable type, but for descriptive purposes it is assumed to be like the one disclosed and described in detail in the Patent #1,633,149, granted to John Wicks, June 21, 1927. In a number of levels in the banks of this and other similar toll transmission selectors in multiple, access is had to a corresponding number of groups of connectors. The bank contact sets of the unequipped levels of the toll transmission selectors, however, are multiply connected to one or more intercepting trunks extending to the intercepting operator's position, such as the trunk comprised in conductors 136' to 139', inclusive, terminating in the jack J² and having the associated trunk circuit TC². The trunk circuit TC² forms a particular part of this invention and will be described in detail subsequently.

The trunk comprising conductors 136 to 139 inclusive and accessible at bank contacts 16 to 19 inclusive terminates in the connector H. The connector H, shown only in skeleton, may be of any suitable type but again for descriptive purposes it is assumed to be like the one disclosed and described in detail in the above referred to patent. In its banks, the connector H together with other similar connectors and also with other local connectors (by which local subscriber to subscriber connections are completed) has access to subscribers' lines, such as the line extending to substation A. The unequipped connector bank contact sets, however, are multiply connected to one or more trunks extending to the intercepting operator's position, such as the trunk comprising conductors 236', 237' and 238', terminating in the jack J³, and having the associated trunk circuit TC³.

With this general description of the object of the invention and the apparatus involved in mind, a detailed description of the operation will now be given.

For this purpose, it will be assumed that the toll operator wishes to extend a connection to the subscriber at substation A. The general operations involved in setting up a toll connection from a toll operator to a

called subscriber are well known, and therefore will be described in a more or less cursory manner. Detailed descriptions of these operations, however, are given in the above referred to patent. To extend a connection to the substation A the toll operator inserts the plug of an idle cord, such as the plug P of the cord circuit O, into the jack of an idle trunk such as the jack J, (the idle condition of the trunk being indicated in any well known manner) and then throws the key K¹ to the left and operates the dial D in accordance with the directory number of the subscriber at substation A. Responsive to the dialing of the first digit, the selector S operates to raise its wipers opposite the corresponding level of bank contacts, and then automatically selects an idle trunk in this level. It may be assumed that the trunk comprising conductors 36, 37 and 38 is the one selected. Responsive to the dialing of the second digit, the toll transmission selector EF operates to raise its wipers opposite the corresponding level of bank contacts and then selects an idle trunk accessible therein. It may be assumed that a trunk line comprising conductors 136 to 139, inclusive, terminating in the connector H is the one selected. When this trunk is seized, in addition to the line relay 201 and the release relay (not shown) of the connector operating, the ring cut-off relay 208 is operated and is locked to the ring control conductor 139. Responsive to the dialing of the next digit of the number the connector H operates and raises its wipers opposite the corresponding level of bank contacts, and responsive to the dialing of the last digit the connector H rotates its wipers into engagement with the set of bank contacts terminating the called line. After completing dialing, the toll operator again restores the key K.

If the called line is busy at this time the connector H functions to connect the busy tone to the talking conductors and furthermore lamp L remains dark. The toll operator on hearing the busy tone (if she still has her listening key K thrown) and noting the dark condition of the lamp L is informed that the subscriber at substation A is busy, whereupon she will release the connection and try again at some later time. If the called subscriber's line is idle at this time, the current flow over the talking conductors 136 and 138 and supplied through the winding of line relay 201 is reversed (by the operation of relay 203). This reversal of current over these conductors causes the operation of polarized relay 103 in the toll transmission selector EF, which locks itself operated and reverses the current flow over the talking conductors 36 and 38, and through the polarized relay 10 in the operator's cord circuit O. As a result relay 10 operates and closes the circuit of lamp L. The light-

ing of the lamp L indicates to the toll operator that the connection has been completed and that the line is idle. (The operation of polarized relay 103 also connects ground and battery to conductors 136 and 137 through the windings of relay 102 in direct opposition to ground and battery connections through the windings of line relay 201. This causes relay 201 to deenergize and close the circuit of relay 200. Relay 200, in operating, prepares the circuits for signalling. Signalling is prevented for the present, since relay 208 is operated.)

When the toll operator is ready to signal the called subscriber, she will throw the key K' momentarily to the right, thereby applying ringing current to the trunk conductors 36 and 38 momentarily. As a result ringing relay 104 in the toll transmission selector 15 EF operates and causes the operation of relay 101 which in turn disconnects ground potential from the ringing conductor 39 connected to conductor 139. This causes the release of the ring cut-off relay 208 in the connector H , as a result of which ringing current is intermittently applied to the called line in the usual manner.

When the called subscriber answers, the ring cut-off relay in connector H again 20 operates and disconnects the ringing current from the called line. Furthermore, relay 102 in the toll transmission selector EF also operates over the called line loop and disconnects ground and battery from the 25 trunk conductors 36 and 38. By reason of the interruption of current flow in the polarized relay 10, this relay again deenergizes and causes the extinguishing of the lamp L . The extinguishing of the lamp L at this time indicates to the toll operator that the called subscriber has answered whereupon the toll operator after informing him that he is wanted in a toll connection permits conversation to take place.

When the subscriber at substation A replaces his receiver at the completion of the conversation, relay 102 deenergizes and relay 10 in the operator's cord again operates and causes lamp L to light. The toll operator, noting this, releases the connection in the well known manner.

In the above descriptions, it was assumed that the toll operator dialed the correct digit in each instance, and obtained connection with the described subscriber. Should the toll operator, however, misdial any one of the digits, the call will be trunked to the intercepting operator (providing of course she does not obtain connection with some other subscriber). The operations which result from the misdialing of each of the digits of a called number will now be described.

It will first be assumed that the toll operator after having extended a connection by 5 way of selector S and toll transmission

selector EF to connector H , misdials one of the last two digits such that the wipers are positioned on an unequipped set of bank contacts connected to the trunk line comprising conductors 236' to 238', inclusive. Finding this trunk idle, the connector H functions in the same way as when operated to connect with an idle line and reverses the flow of current over the trunk conductors 136 and 138, which finally results in the operation of the polarized relay 10 in the operator's cord circuit O as previously described. Again lamp L lights, indicating that a connection has been completed. When the operator wishes to signal she again operates key K' to the right momentarily. As a result the connector H functions to connect ringing current to the trunk conductors 236' and 238' intermittently in the regular manner. Responsive to the ringing current, relay 153 of the trunk circuit TC^3 operates, locking up mechanically to the armature of relay 152, and closing the circuit of lamp L^3 .

On perceiving the lighted condition of the lamp L^3 , the intercepting operator will insert the plug P' of the cord circuit O' into the jack J^3 and will then operate the listening key K^2 . If the operator inserts the plug in the jack during a ringing period, relay 54 is operated by the ringing current and by separating contacts 65 prevents any further operation from taking place. At the commencement of the next silent period, relay 54 deenergizes and by permitting contacts 65 to close completes a circuit for relay 51 in series with relay 152. Relay 152, in operating, unlocks the mechanical lock holding relay 153 operated, and by separating contacts 155 opens the ringing bridge across the talking conductors. Relay 153, in releasing its armature, separates contacts 156 and opens the circuit of lamp L^3 .

Relay 51 of the cord circuit O , being energized in series with relay 152, connects ground potential to the upper and lower terminals of the impedance coil 50. As a result the ring cut-off relay 200 in the connector H energizes and disconnects the ringing current from the trunk conductors and completes points in the talking connection. By the closure of contacts 55 a circuit is established for relay 53. Relay 53 operates and opens points in the talking leads of the cord circuit at contacts 62 and 64, and by closing contacts 63 closes the circuit of relay 52. Relay 52 operates in parallel with relay 51 and by closing contacts 58 and 61 closes points in the talking leads of the cord circuit. By the closure of contacts 60 relay 52 establishes a locking circuit for itself independent of relay 53, and by separating contacts 59 the circuit of relay 51 is opened. Relay 51 now deenergizes and disconnects ground from the terminals of the impedance

coil 50 by separating contacts 57, and opens the circuit of relay 53 by separating contacts 55. Relay 53 thereupon falls back and opens the initial circuit of relay 52 by separating contact 63 and by permitting contacts 62 and 64 to close again closes points in talking leads of the cord circuit so that the intercepting operator's head set may now be connected across the trunk conductors. The purpose of the foregoing operations is to prevent a talking circuit from being completed to the intercepting operator's head set, should she have the listening key K^2 thrown, until the ring has been tripped to prevent her from receiving disagreeable noises in her ear as would be produced when the ring was being tripped, if her head set were connected across the line at that time.

After ground is disconnected from the terminals of the impedance 50, relay 102 in the toll transmission selector operates over the loop including impedance 50 and resistances R' and R^2 in series and as before, by disconnecting ground and battery from the trunk conductors 36 and 38, causes relay 10 in the toll operator's cord to release and extinguish the lamp L . This informs her that the extended call has been answered, whereupon she will operate her key K , if it is not already operated, with the intention of informing the called subscriber that he is wanted in a toll connection. Instead, however, the intercepting operator will answer and inform the toll operator that she has dialed the wrong number and give her such information as she may have concerning the called subscriber.

Should the intercepting operator need to look up some matter for the toll operator, she may do so, and can refresh the toll operator by operating the flash key K^3 intermittently when she wishes to recall the toll operator. This opens and closes the circuit of relay 102 in the toll transmission selector EF , which causes lamp L to flash.

After receiving this information the toll operator will remove her plug P from the jack J , and the intercepting operator will remove the plug P' from the jack J^3 , thus causing the release of the connector in the usual manner. Removing the plug P' from the jack J^3 also opens the circuit of relay 52 of the cord circuit O' and relay 152 of the trunk circuit TC^3 whereupon these relays restore to normal.

As previously described, the banks of the toll connector H are multiplied with those of other local connectors, which are accessible to other local subscribers for completing regular local connections. Therefore, should a regular subscriber, in attempting to establish a connection with the subscriber at substation A, dial a wrong number he may also obtain connection with the trunk line comprising conductors 236' to 238', inclusive.

In such a case, the intercepting operator would answer the call by inserting the plug P' into the jack J^3 in the same manner as described above. When such a call is answered, the ring cut-off relay of the regular connector (not shown) over which the connection is extended is operated by the closure of contacts 57 by the operation of relay 51 (the back bridge relay of the connector being prevented from operating since the winding of the back bridge relay connected to ground is shunted). After relay 51 deenergizes and opens contact 57, the back bridge relay is still prevented from operating by reason of the combined resistance of coil 50 and resistances R' and R^2 limiting the current flow to too low a value. However, as described above, the battery feed relays, such as relay 102, of the toll transmission selectors are adjusted to operate in series with impedance 50 and resistances R' and R^2 .

Since the back-bridge relay of a local connector is not operated when a call is extended to, and answered by, the intercepting operator (to prevent a local subscriber from being charged for such a call), a connection of this kind is released as soon as the local subscriber replaces his receiver. Since this places the intercepting trunk used in an idle condition immediately, it is quite possible for another connection to be extended to this same trunk before the intercepting operator has removed the plug P' from the jack J^3 of the trunk. According to a particular feature of this invention the ring will be tripped, nevertheless, and the intercepting operator may answer this second call without removing the plug from the jack. To describe this feature, it will be assumed that before the intercepting operator removes the plug P' from the jack J^3 , after answering one call over this trunk from a local subscriber another connection is extended to this same trunk. Relay 54 again operates from ringing current (applied to the trunk conductors by the connector used in the second connection) and opens the circuit including relay 52 and 152 in series. Relay 152 in deenergizing again closes the ringing bridge including ringing relay 153 across the trunk conductors. Therefore, relay 153 is again operated by ringing current and the lamp L^3 is lighted.

At the end of the ringing period in which relay 54 was operated, relay 54 releases and in so doing, permits relays 51, 53 and 52 to operate and trip the ring and close the talking circuit to the intercepting operator's head set as previously described. Relay 152 in operating (first in series with relay 51 and then in series with relay 52) again opens the ringing bridge across the trunk conductors, causing relay 153 to deenergize and extinguish the lamp L^3 .

5 The second lighting of lamp L^2 is of course more or less in the nature of a flash; but the intercepting operator is not wholly dependent upon the perception of this flash to indicate to her that a second connection has been extended. During the instant after ringing current is applied to the trunk conductors and before relay 52 is released by the operation of relay 54, ringing current 10 passes through the intercepting operator's head set, giving her a decided click, which is further indication that a second connection has been extended to her. She may answer this second connection as she did the first 15 without any further procedure.

To further describe the invention, it will be assumed that the toll operator in attempting to extend a connection to a called subscriber sets up a connection through selector S to the toll transmission selector EF, and then makes a mistake in the next digit and as a result causes the toll transmission selector EF to extend the connection to the intercepting operator over the trunk comprising conductors 136' to 139' inclusive. When this trunk is connected with, ground potential is connected to both the regular release conductor 137' and the ring control conductor 139'. Relay 104' is energized 20 from ground on conductor 137', the circuit including contacts 106 and contacts 109, and in operating opens a point in the circuit of the lamp L^2 at contacts 112, opens a point in the ring-back tone circuit by separating contacts 115, closes the circuit for relay 103' by closing contacts 114, and closes a locking circuit for itself at contact 113 in series with relay 105 and the ring control conductor 139'. Relay 103' operates 25 and closes a point in the circuit of lamp L^2 at contacts 108, closes a point in the ring-back tone circuit at contacts 111, opens a point in the initial energizing circuit of relay 104' by separating contacts 109, and by 30 closing contacts 110 closes a locking circuit for itself independent of relay 104'. Relay 105', in energizing, connects ground and battery potential through protecting resistances to the upper and lower talking conductors of the trunk line respectively.

55 As a result, polarized relay 103 in the toll transmission selector EF operates and locks and reverses the direction of current flow over the trunk conductors 36 and 38. The operator, however, not knowing that she has obtained connection with a trunk line leading to the intercepting operator's position, continues to dial, but further dialing has no effect. When she has completed the 60 dialing she restores the key K' to normal. Polarized relay 10 now operates and causes lamp L to light. This normally indicates to the toll operator that the call has been extended.

65 Again when the toll operator wishes to

signal, she operates the key K to the right momentarily. As a result, ringing relay 104 in the toll transmission selector EF operates and causes the removal of ground potential from the ringing control conductor 139, which now opens the locking circuit of relay 104' in series with relay 105'. Relay 105' deenergizes and in restoring removes the battery and ground connections from the trunk conductors 136 and 138. 70 Relay 104' deenergizes and in so doing, closes the circuit of lamp L^2 at contacts 112, opens a point in its own locking circuit at contacts 113, opens the initial energizing circuit of relay 103' at contacts 114, and 75 closes the ring-back tone circuit at contacts 115. The toll operator (if her key K is operated) hears the ring-back tone, indicating that signalling is taking place.

The lighting of the lamp L^2 signals the 80 intercepting operator. The intercepting operator answers the call by inserting the plug P' of the cord circuit O' into the jack J^2 . As a result relay 102' operates over its lower winding in series with relay 51 of the 85 cord circuit O'. Relay 102', in operating, closes a locking circuit over its upper winding and at the same time opens the locking circuit of relay 103'. Relay 103' falls back and opens the circuit of the lamp L^2 at contacts 108, opens a point in its own locking circuit by separating contacts 110, and opens the ring-back tone circuit at contacts 111. In the cord circuit O', relays 51, 53 and 52 operate in the same sequence as described previously, but without any real function in this case other than to close points in the talking leads. After relay 51 has fallen back after being operated, relay 102 in the toll transmission selector operates over the loop including impedance 50 and resistances R' and R^2 and, as before, disconnects ground and battery from the trunk conductors 36 and 38, causing polarized relay 10 to release and extinguish 90 the lamp L. This signals the toll operator who then connects her head set to this trunk by operating key K, providing it is not already connected thereto. The intercepting operator answers and informs the toll operator of her mistake.

95 It should be noted that should the intercepting operator answer immediately, that is, while the toll operator still has the key K' thrown to the right, ringing current will be induced in the secondary windings of the repeating coil R of the toll transmission selector EF and cause the operation of relay 54. The operation of relays 51, 52 and 53 is thus delayed until 100 after the ringing current ceases, and by preventing the completion of the talking connection (should the key K^2 be operated) to the intercepting operator's head set, until after ringing current has ceased, the 105 110 115 120 125 130

possibility of the operator receiving disagreeable noises in her ear is eliminated.

After the toll operator has been informed of her mistake, she will remove the plug P 5 from the jack J, and the intercepting operator will remove the plug P' from the jack J^a, causing the release of the connection in the usual manner. Removing the plug P' from the jack J^a also opens the circuit of relay 52 and relay 102'. Relay 52 restores and relay 102' likewise restores after the circuit of its upper winding is opened upon the release of the toll transmission selector EF.

15 It should be noted that since relay 102' is locked up over its upper winding, this relay would not deenergize until after the toll transmission selector EF was released, should the intercepting operator be the first 20 to withdraw her plug P' from the jack J^a. This prevents a false reoperation of relays 103', 104' and 105' which would otherwise take place in such case.

To further describe the invention, it will 25 be assumed that the toll operator after inserting the plug P into the jack J and throwing the key K' to the dialling position, with the intention of extending a connection to some subscriber, dials the wrong first digit 30 and as a result causes the selector S to extend the connection to the intercepting operator over the trunk comprising conductors 36', 37' and 38', terminating at the jack J'. When the connection is extended to this 35 trunk line, line relay 73 of the trunk circuit TC' operates and closes the circuit of release relay 74. Release relay 74 operates and places ground potential on the release conductor 37' to maintain the selector S operated and mark the trunk busy. The line relay 73 energizes and deenergizes correspondingly responsive to the dialing of the remaining digits of the called number, but without effect. The circuit of relay 74, is 40 opened each time relay 73 deenergizes, but being slow to release relay 74 maintains its armature attracted continuously.

When the toll operator has completed dialing, she restores the key K' to normal. 50 The current now passes through the winding of the polarized relay 10 from the battery supplied through the windings of the line relay 73 of the trunk circuit TC', the direction being such as to cause this relay 55 to operate and light the lamp L. Thus the operator is given the same indication as though the connection has been extended to the desired substation.

When the operator is ready to signal, she 60 again operates key K' to the right momentarily applying ringing current to the line conductors. This causes the operation of the ringing relay 72. Relay 72 locks itself to the armature of relay 71, mechanically, 65 closes a point in the ring-back tone circuit

at contacts 80, and closes a circuit for the lamp L' at contacts 79. The toll operator hears the ring-back tone, providing she has her key K operated. The lighting of the lamp L' indicates to the intercepting operator that a call has been extended to her position. 70

The intercepting operator answers the call by inserting the plug P' into the jack J' and operating her listening key K' (if it is not already operated). Inserting the plug P' into the jack J' closes a circuit for relay 71 in series with relay 51. Relay 71 operates and disconnects the battery feed relay 73 and also the ringing relay 72 from the trunk conductors at contacts 77 and 78, and closes another circuit for relay 74 at contacts 76. In operating its armature, relay 71 unlocks the armature of relay 72. The restoration of the armature of relay 72 opens the circuit of the lamp L' and opens the ring-back tone circuit. Disconnecting the battery feed relay from the trunk conductors opens the circuit for the polarized relay 10 in the toll operator's cord circuit. Relay 10, in restoring, extinguishes the lamp L, which signals the toll operator. The toll operator then connects her head set to this trunk and is then informed of her mistake by the intercepting operator. 80 90 95

After receiving this information the toll operator removes the plug P from the jack J, and the intercepting operator removes the plug P' from the jack J'. The latter operation opens the circuit of relay 52 in series with relay 71, both of which restore to normal. Relay 74 likewise restores to normal after its circuit is opened at contacts 76, and by removing ground from the conductor 37', permits the selector S to restore. 100 105

This completes the description of the invention. What is thought to be new and is desired to have protected by Letters Patent is specifically stated in the appended claims.

What is claimed is:

1. In a telephone system, an operator's switchboard, a trunk terminating in a jack at said switchboard, means including a connector switch for extending a connection to said switch via said trunk, means in said connector including a ring cut-off relay for applying ringing current to the conductors of said trunk line after said connection is extended, an operator's cord terminating in a plug, and means in said cord responsive to the insertion of said plug into said jack to answer the call, and responsive to the extension of the connection providing said plug is in said jack at the time the connection is extended for operating said ring cut-off relay. 110 115 120 125

2. In a telephone system, a trunk line, an operator's cord adapted to be connected to said trunk line, means for establishing a connection to said trunk line and for applying 130

ringing current thereto, and means responsive to the connection of said cord to said trunk line to answer the call, and responsive to the establishment of said connection providing said cord is connected to said trunk line at the time the connection is established for tripping the ring.

3. In a telephone system, a trunk line, an operator's cord adapted to be connected to said trunk line, means for establishing a connection to said trunk line and for applying ringing current thereto, means responsive to the connection of said cord to said trunk line to answer the call, and responsive to the establishment of said connection providing said cord is connected to said trunk line at the time the connection is established, for tripping the ring, an operator's head set normally disconnected from said cord, and means for automatically connecting said head set to said cord a moment after the ring is tripped.

4. In a telephone system, a trunk line, an operator's cord adapted to be connected to said trunk line, means for extending calls to said trunk line and for applying ringing current thereto each time a call is extended, tripping means responsive to the connection of said cord to said trunk line to answer a call for tripping the ring, and means for causing said tripping means to reoperate providing a second call is extended to said trunk line before said cord is disconnected therefrom after answering the first call.

5. In a telephone system, a trunk line, an operator's cord adapted to be connected to said trunk line, means for extending calls to said trunk line and for applying ringing current thereto each time a call is extended, tripping means responsive to the connection of said cord to said trunk line to answer a call for tripping the ring, means for causing said tripping means to reoperate providing a second call is extended to said trunk line before said cord is disconnected therefrom after answering the first call, an operator's head set normally disconnected from said cord, and means for automatically connecting said head set to said cord a moment after each operation of said tripping means, said last means being deactuated when a second call is extended by the means for causing said tripping means to reoperate.

6. In a telephone system, a trunk line, an operator's cord adapted to be connected to said trunk line, means for extending calls to said trunk line and for applying ringing current thereto each time a connection is extended, an operator's head set normally disconnected from said cord, means responsive to the connection of said cord to said trunk to answer a call for tripping the ring and for connecting said head set to said cord after the ring is tripped, and means for deactuating said last means and causing its

reoperation responsive to the extension of a second call to said trunk line before said cord is disconnected therefrom after answering a previous call.

7. In a telephone system, a trunk line including a ring control conductor and a release conductor terminating at an intercepting operator's switchboard, an automatic switch and means controlled by a toll operator for operating said switch to connect with said trunk line to extend a call, a first and a second relay for said trunk line, means in said switch for closing a circuit including said release conductor for said first relay to cause the same to operate, means controlled by said first relay for closing a holding circuit including said ring control conductor for itself, and for closing a circuit including said release conductor for said second relay to cause it to operate, means controlled by said second relay for opening the initial circuit of said first relay and for closing a locking circuit including said release conductor for itself, a signal and a circuit therefor including normally open contacts on said second relay and normally closed contacts on said first relay, means in said switch controlled by the toll operator for opening the holding circuit of said first relay to cause the same to deenergize and close the circuit of said signal to cause the signal to operate and signal the intercepting operator, and means responsive to the answering of the call for opening the locking circuit of said second relay to cause said second relay to deenergize and open the circuit of said signal.

8. In a telephone system, a trunk line including a ring control conductor and a release conductor terminating at an intercepting operator's switchboard, an automatic switch and means controlled by a toll operator for operating said switch to connect with said trunk line to extend a call, a first and a second relay for said trunk line, means in said switch for closing a circuit including said release conductor for said first relay to cause the same to operate, means controlled by said first relay for closing a holding circuit including said ring control conductor for itself, and for closing a circuit including said release conductor for said second relay to cause it to operate, means controlled by said second relay for opening the initial circuit of said first relay and for closing a locking circuit including said release conductor for itself, a signal and a circuit therefor including normally open contacts on said second relay and normally closed contacts on said first relay, means in said switch controlled by the toll operator for opening the holding circuit of said first relay to cause the same to deenergize and close the circuit of said signal to operate and signal the intercepting operator, means responsive to the

answering of a call for opening the locking circuit of said second relay to cause said second relay to deenergize and open the circuit of said signal, a second signal at the 5 toll operator's position, and a third relay for said trunk energized in series with said first relay for controlling the operation of said second signal.

9. In a telephone system, a trunk line, 10 a switch and means for operating it to connect with said trunk line to extend a call, a first and a second relay for said trunk line, means in the switch for closing an initial circuit for the first relay to operate the same, 15 means controlled by the first relay for closing a holding circuit for itself and for closing an initial circuit for the second relay, means controlled by the second relay for closing a holding circuit for itself and for 20 opening the initial circuit for the first relay,

a signal and a circuit therefor including normally open contacts on the second relay and normally closed contacts on the first relay, means in the switch operable at will for opening the holding circuit of the first relay 25 to cause the same to deenergize and close the circuit of the signal, a cord circuit and means for connecting it to the trunk line to answer the call, a third relay for said trunk and means for operating it when the cord 30 is connected to the trunk to open the holding circuit of the second relay, and separate means for maintaining the third relay operated after the cord circuit is disconnected from the trunk to prevent the first and the 35 second relay from reoperating.

In witness whereof, I hereunto subscribe my name this 22d day of June, A. D. 1927.

THOMAS F. CROCKER.
